COMBINED MERCHANTISE DISPLAY STAND
AND ADVERTISING CARD HOLDER

Marcus Glaser, San Francisco, Calif., assignor to Glaser
Bros., San Francisco, Calif., a corporation of California

Filed Feb. 8, 1960, Ser. No. 59,296

Term of patent 14 years

(Cl. D80—10)

FIG. 1

Fig. 1 is a top perspective view of a combined merchandise display stand and advertising card holder embodying my new design;

Fig. 2 is a top plan view thereof;

Fig. 3 is a bottom plan view thereof; and

Fig. 4 is a side elevational view thereof.

I claim:

The ornamental design for a combined merchandise display stand and advertising card holder, as shown.
